(57) **CLAIM**

The ornamental design for a drawer track locator, as shown and described.

DESCRIPTION

FIG. 1 is a front, right, and top perspective view of a drawer track locator, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1 comprising a screw part; and,

FIG. 10 is a partial enlarged view of an area labeled 10 in FIG. 2 comprising an adjustment part.

The broken lines shown in the drawings are included for the purpose of illustrating portions of the drawer track locator that form no part of the claimed design.
